UNITED STATES PATENT OFFICE.

JEROME SANDIN, OF WILKINS TOWNSHIP, ALLEGHENY COUNTY, PENNSYLVANIA,
ASSIGNOR TO WESTINGHOUSE ELECTRIC & MANUFACTURING COMPANY, A COR-
PORATION OF PENNSYLVANIA.

LOCOMOTIVE FUSE.

Application filed September 7, 1927. Serial No. 218,041.

My invention relates to fuses, and particularly to fuses of the expulsion type wherein one end of the fuse casing is open and from which the gases incident to the rupture of 5 the fuse is discharged.

An object of my invention is to provide an expulsion fuse wherein the closure for one end of the fuse casing constitutes a clamping terminal wherein good conductive contact is 10 insured.

Another object of my invention is to provide an expulsion fuse wherein the fusible element is provided with a terminal disc that may be securely clamped upon a terminal seat 15 by means of a threaded closure plug or cap and wherein the fusible element is provided at its outer end with a weakened section or terminal that is attached to the fusible strip with a solder having a low melting point, the 20 connection being of such character that it is severed by the heated gases incident to the rupture of the inner end of the fuse, thereby facilitating the expulsion of the fusible element from the casing.

25 A further object of my invention is to provide an expulsion fuse having the above noted characteristics, wherein the fusible element is provided with a portion having reduced current carrying capacity to insure initial 30 rupture of the fuse at a point near the enclosed end of the casing and to provide such a fusible element with an outer terminal that is soldered thereto, and which is severed from the fuse strip by the heated gases incident to 35 the rupture of the fuse.

These and other objects that will be made apparent throughout the further description of my invention are attained by means of the fuse apparatus hereinafter described and 40 illustrated in the accompanying drawings, wherein,

Figure 1 is an elevational view of an expulsion fuse embodying features of my invention,

45 Figure 2 is an end view of the fuse shown in Fig. 1,

Figure 3 is a longitudinal section through the fuse shown in Fig. 1,

50 Figure 4 is a transverse section taken on the line IV—IV of Fig. 3,

Figure 5 is a perspective view of a fragment of the fuse element, and

Figure 6 is a perspective view of a modified form of fusible refill.

Referring to the drawing, the fuse comprises an insulating tubular casing 6 that is provided at one end with an internally threaded ferrule 7 having an annular contact seat 8 for receiving the terminal of a fuse element. 55 The fuse element comprises a terminal disc 9 to which a fusible strip 11, preferably made of zinc, is attached by means of a rivet 12. The end of the fusible strip 11 near the terminal disc 9 is provided with a hole 13 for reducing the current carrying capacity of the fuse 60 strip at this point and for insuring initial rupture of the fuse near the inner end thereof.

The terminal disc 9 is mounted upon the contact seat 8 of the ferrule 7 and is clamped in conductive engagement therewith by 70 means of a threaded closure plug 14 which is screwed into the threaded portion of the ferrule 7 and into engagement with the outer face of the disc 9, thereby securely clamping the disc in operative position. The plug 14 75 is provided with a slot for receiving a screw driver or other implement for turning the plug.

The outer lower end of the casing 6 is 80 provided with a terminal sleeve 16 having a terminal seat 17 for receiving the outer terminal of the fuse strip 11. The outer terminal comprises a metal strip 18 preferably made of copper and which is non-fusible under ordinary operating temperatures. The 85 copper strip is secured to the outer end of the fuse strip 11 by means of a solder fusible at relatively low temperatures, the purpose being to provide a connection that will be severed by the heated gases incident to the 90 rupture of the inner end of the fuse. It will be understood that the soldered joint is of greater current carrying capacity than the reduced portion of the fuse at the hole 13 and the fuse will not be ordinarily severed at the 95 soldered joint by reason of current passing therethrough.

In Fig. 6 I have shown a modified form of fusible element or refill wherein the strip is provided with a hole 10 smaller than the 100 hole 13 that causes fusion at that point after the element fails at the hole 13. The current carrying capacity of the element adjacent the hole 10 is greater than that adjacent the hole 13. The inner end of the element is bent to 105 form a contact terminal, the element being adapted to be inserted through a slot in a flat contact disc.

It has been found that fuses of the expulsion type having no facilities for severing them adjacent the open end at the time of rupture, sometimes remain in the casing and cause abnormal continuation of the arc. This is particularly true where the fuse has been ruptured under overload conditions and wherein the explosion is not as violent as is the case when ruptured under short circuit conditions. It is of great importance to insure elimination of the fuse from the casing the instant the fuse ruptures, and by providing the soldered connection to the outer terminal, it has been found that the solder melts almost instantly and releases the fuse strip before it has had opportunity to volatilize.

It has heretofore been the practice to provide expulsion fuses with auxiliary casings which are expelled by the gases incident to the rupture of the fuse, such casings being open at both ends and supported within the outer casing by means of the fuse element which is bent across the outer end thereof and secured to an outer terminal. The auxiliary casing serves to elongate the insulated barrier between the inside terminal and the exterior terminal when rupture occurs.

An auxiliary insulating tube 19 is provided within the casing 6, for the above mentioned purpose, but in order to facilitate the rapid expulsion of the tube 19, the outer end of the tube 19 is provided with an insulating bushing 21, that partially closes the outer end of the tube. The bushing is provided with a central opening 22 through which the terminal strip 18 extends into the casing, the point of joinder with the end of the fusible strip being located directly above the bushing 21 in order that the point of joinder is located at a point of highest concentration of the escaping gases. The instant the fuse ruptures, the gases are discharged from the casing, carrying with it the auxiliary casing 19. The heated gases immediately sever the fuse strip from the terminal 18 which at this time is moving downward with the auxiliary casing after initial rupture of the fuse strip at its inner end.

The terminal strip 18 is clamped to the contact seat 17 by means of a plate 23 that is detachably secured to the clamping seat 17 by means of screws 24.

The expulsion fuse above described is supported vertically upon an insulating base 25 that may be attached to any desired support. The base 25 is provided with contact clips or jaws 26 and 27 in which the fuse casing is detachably mounted. The clip 28 is secured to the contact jaw 26 and extends over the

closed end of the casing for preventing the recoil incident to the explosion of the fuse from longitudinally displacing the casing out of the clips.

By reason of the terminal constructions above described, the removal and replacement of a fuse element is greatly facilitated and because of the construction of the fuse strip, the operation of the fuse element is improved under both overload and short circuit conditions.

While I have illustrated but one embodiment of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. An expulsion fuse comprising a casing closed at one end, a fuse strip extending through the casing and having a portion for initiating rupture thereof near the closed end of the casing, an auxiliary casing within the first casing through which the fuse strip extends and having a restricted opening adjacent its outer end, the said fuse strip having a terminal adjacent the open end of the casing attached thereto by solder fusible by the gases incident to rupture of the said portion and extending exteriorly of the casing.

2. An expulsion fuse comprising a casing closed at one end, a fuse strip extending through the casing and having a portion for initiating rupture thereof near the closed end of the casing, an auxiliary casing within the first casing through which the fuse strip extends and having a restricted opening adjacent its outer end, the said fuse strip having a terminal adjacent the open end of the casing, attached thereto by solder fusible by the gases incident to rupture of the said portion and extending exteriorly of the casing and supporting the auxiliary casing.

3. An expulsion fuse comprising a tubular casing closed at one end, an auxiliary tubular casing within the first casing and having its outer end partially closed and a fusible element connected to a terminal near the closed end of the casing and extending through the auxiliary casing and projecting through the outer end thereof into engagement with a terminal, the said fusible element serving to releasably support the said auxiliary casing.

In testimony whereof, I have hereunto subscribed my name this 29th day of August, 1927.

JEROME SANDIN.
